UNITED STATES PATENT OFFICE.

EPIPHANE P. SIMARD, OF WALTHAM, MASSACHUSETTS.

RAIL GRINDER.

1,405,019.

Specification of Letters Patent. Patented Jan. 31, 1922.

Application filed November 7, 1919. Serial No. 336,350.

To all whom it may concern:

Be it known that I, EPIPHANE P. SIMARD, a citizen of the United States, residing at Waltham, in the county of Middlesex and 5 State of Massachusetts, have invented certain new and useful Improvements in Rail Grinders, of which the following is a specification.

This invention relates to portable rail 10 grinders adapted especially for use on street and electric railways where there are many cars passing and where it is necessary to frequently remove the rail grinder from the tracks.

15 For this purpose it is desirable that the rail grinder should be so light as to be readily removed; that it should be equipped with devices whereby it can be readily removed; that the adjustment for the grinding 20 operation should be rapid; that it should be capable of taking curves and grinding curves without special adjustment; and that vibration of the wheels, frame or grinding parts should be avoided.

25 There are some types of such machines which are devised for grinding at a gradual slant from the bottom of depressions in the rails, so that a sharp depression will be smoothed down and the jolting of the cars 30 eliminated. My present device might be used for this purpose, but it is intended more particularly for use where depressions have been filled by welding material and where there is an excess of such material 35 which must be smoothed or ground down, to make the rail surface straight.

I accomplish the above purposes by providing a relatively light machine including a movable carriage with the supports on the 40 operating side relatively close together, and preferably the wheels which run on the other track somewhat smaller so that the carriage will cant slightly in that direction. On this carriage I provide a rigid 45 framework near the operating side having rigid vertical guideways, and vertically slidable in these guideways I provide a rigid, movable frame which carries a motor, preferably an electric motor, and rigid bearings 50 in which is a shaft revoluble by the motor which carries a grinding tool, such as an emery wheel, in a position to be forced in contact with the rail on the operating

side by means of an adjusting screw which passes through the framework and is 55 adapted to raise and lower the frame in the guideways, carrying with it the motor and grinding tool. I also preferably provide derailing wheels which project from the carriage on the operating side in such manner that the carriage and all the parts can be tilted over on that side until the derailing wheels strike the ground, at which point the center of gravity has been so shifted 60 that the whole device can be pushed from 65 the track like a double wheel wheelbarrow.

I use no adjustable grinder carrying arms, but the location of my framework, frame, motor, grinding means and derailing wheels, all being proximate the operating 70 side, provides enough weight to hold the grinding means in contact with the rail and permits the centre of gravity to be easily shifted for derailing, while the weight so placed, the rigidity, and the compactness of the parts prevent vibration of 75 the grinding means and thus prevent uneven work.

In the drawings, Fig. 1 is a perspective view of two street car rails, with my rail 80 grinder in operating position.

Fig. 2 is an enlarged or exaggerated view showing a section of rail in which a depression has been welded, all of the parts being exaggerated to show the principle. 85

Fig. 3 is an elevation from the operating side of my machine, some parts being shown in section.

Fig. 4 is a plan view of my machine, some parts being broken away. 90

Fig. 5 is a sectional elevation looking down on the line 5—5 of Fig. 3, other parts being shown in section and a regular grinding wheel being shown in position.

Fig. 6 is an elevation showing a modification of my construction, and Fig. 7 is a plan view of another modification. 95

Fig. 8 is a diagrammatic elevation from the operating side showing the relation of the supporting wheels and runner to the 100 grinding wheel.

Fig. 9 is a side elevation partly broken away showing my improved form of rail runner.

Fig. 10 is a section on line 10—10 of 105 Fig. 9.

Fig. 11 is a side elevation showing part of the inside movable frame with attachment for side grinding, the bearing 44 being removed.

5 Fig. 12 is an elevation from the back, partly in section, and detail of the construction shown in Fig. 11.

Fig. 13 is a detail side elevation of another method of transmitting power.

10 My invention comprises a movable carriage, indicated by B, having, on what I will call the operating side, small railroad truck wheels F, F located one behind the other and relatively a short distance apart, and 15 at the other side similar wheels C, C which preferably are somewhat smaller in diameter than those marked F, F. I show the springs 7, 7 between the frame and wheels C, C which cause these wheels to adjust themselves to slight variations in gauge and when 20 taking curves.

In the drawings, I show this carriage made up of angle irons, such as 13, 13, at the front and back, inside bars 14, 14 parallel with 13, and side bars 15, 51, all suitably fastened together.

The interior bars 14 are shown as extending out beyond supporting wheels C and terminating in handles D, D, which are a 30 suitable distance apart, for the convenience of one man in lifting. On the operating side, these inside bars 14 extend well out beyond the supporting wheels F as shown at 16, 16, and they carry at their ends bearings 35 50 for the axle or bar 51 which carries derailing wheels G, which thus project from the carriage on the operating side. These derailing wheels, as shown in Fig. 1, when the machine rests on the rails A, do not 40 touch the ground, but when the handles D are lifted, they strike the ground and a continuation of the lifting will shift the pivotal point from wheels F to wheels G, allowing the device to be readily moved off from the 45 tracks. It can be as readily replaced on the tracks.

At the top, on the side of carriage B proximate the operating side and wheels F, I show a framework H built up of angle irons 50 60, 61, bent and bolted to the front and back bars 13 and inside bars 14, as shown at 62, 62, 63, 63, and connected by the top bars 64 and 65. To these top bars is fixed a bed plate 66 which carries the adjusting wheel 55 20 for the screw P. 67 is a stiffening brace.

Attached to the inside bars 14 are also the 60 four vertical guideways 12, each of which is preferably channeled, as at 10, to receive a guiding part 11 bolted to the rigid frame K, which is thereby slidable vertically inside framework H.

This slidable frame is shown as having front and back bars 70 which carry guide members 11, side bars 71 and 75, vertical 65 U-shaped uprights 72 and 73, which are also

connected by parallel bars 74, between which is bolted a screw plate 75, to which is fixed the end of screw P.

This frame should be so made that it will be very rigid and so that it can slide up and down in the guideways in accordance with the way in which wheel 20 is turned. Rigidly fastened to frame K is a motor L, shown as an electric motor, controlled by a rheostat O and supplied with power by 75 means of a wire R which connects it to the trolley wire in a well known manner.

The front and back bars 70 of frame K extend out beyond the wheels F on the operating side and are connected by means of 80 bar 75. This bar 75 carries one bearing 44 for grinding shaft 42, the other bearing 45 being carried by another brace bar 76 of the frame K, as shown in Fig. 5. These bearings are rigidly carried by frame K, 85 and the grinding shaft 42 is revoluble therein.

This shaft 42 is shown as carrying a grinding wheel M, which is of any usual type, and as extending into slidable frame K, and 90 as carrying on its inner end a sprocket or pulley 46 which is driven by a chain 41 from a similar sprocket or pulley 47 carried by the shaft 40 of motor L.

The shaft 42 can be removed to replace 95 wheel M by removing bearings 44 and 45 or by removing nuts 130, 131, 132. Collars 133 hold M to 42.

In the operation of such devices, a depression, such as shown at 90 in Fig. 2, in the 100 rail A, is filled with welding material, such as W, which usually more than fills up the depression, leaving a mound which must be ground down.

In the operation of my machine, the 105 grinding wheel is adjusted by means of the wheel 20 to a point slightly below 91 the top level of this mound, as indicated at 92. The motor is started and the carriage is pushed back and forth, preferably by means 110 of the handles 97, and when the level 92 is ground down, the grinding wheel is successively set at 93, 94, 95, and finally at 96, which corresponds with the top of the rail.

In place of the wheels F, F on the operating side, I may, as shown in Fig. 6, use runners 101 and 102, between which is located the grinding wheel M. This is especially useful where the rail A is corrugated with high spots 103 and low spots 104, as in this 120 case the runners do not drop into the depressions but keep the grinding wheel on a uniform level.

As shown in Fig. 6, the grinding wheel may be fixed directly to the shaft 40 of motor L which may be set low in frame K to permit thereof.

As shown in Fig. 7, instead of the two supporting wheels C, C, I may use a single runner, such as 105, carried by a suitable 130

V shaped connection 106, connected to the inside bars 14.

I may leave out the flanges, such as shown at 107, and may use for the forward supporting means on the operating side a runner, such as T, retaining the wheel F at the rear on the operating side and the wheels C, C on the other side. As the wheels C, C and F are flanged, it is not necessary to have a flange, 10 if such runner T is used only on the forward side, as shown in Fig. 8.

A decided advantage of this arrangement is that where the rail is corrugated, as shown at 104 in Fig. 8, the runner T runs over it, 15 striking the higher spots and keeping the level, while the grinding wheel M is grinding off the rough spots in such manner that, after it has passed, the part 108 is smooth and level so that there is no tendency for the follower 20 wheel F to drop into depressions or rise on elevations.

For certain classes of work, I prefer to make this runner of the form shown at V in Figs. 9 and 10, with a longitudinal channel 25 120, and preferably with upturned ends 121, 121, and revoluble in this channel the series 30 of aligned rolls 122, shown as held in place by headed pins 123 and cotter pins 124. It is evident that these rollers 122, being arranged accurately in line, permit the runner V to travel over uneven surfaces on a level, as they strike only the high spots. At the same time, they permit the whole machine to be moved about with more facility than where 35 a runner, such as 101, 102 and 105, without rollers, is used.

I prefer to use with this construction a fin flange 125 which serves the same purpose as flange 107.

40 My rail grinder can also be used for grinding the side, as well as the top, of a rail, by using a thin grinding wheel, such as S shown in Fig. 11, which can be lowered down by suitable means alongside the rail to even it 45 up, as by cutting off any surplus welding material or by smoothing out lateral corrugations.

In Figs. 11 and 12, I show a construction 50 for grinding the side of the rail which I find very satisfactory. In this construction, a pivot bar 110 is riveted or otherwise fastened between the uprights 73 on the operating side of the frame K, and this pivot bar carries a suitable bearing 111 for a hand lever 112. This hand lever is forked at 113 and carries pins 114 which enter suitable holes in a collar 115, which is carried by a sleeve 116, which also carries the thin grinding wheel S.

60 This sleeve 116 is slidable on shaft 42 and it, with wheel S, is revoluble thereby through the medium of a spline 117.

When it is desired to grind the side of a rail or the side of a groove, such as 118 65 shown in Fig. 12, the frame, motor and

grinding wheel are all lowered down by means of screw P, and then by means of handle 112, the grinding wheel is moved, operated and manually controlled as the carriage is moved back and forth on the rail. 70

As shown in Fig. 13, instead of a chain or belt connection between the motor shaft 40 and the grinding shaft 42, I can use the gears 120, 121 and 122 in a well known manner. 75

I claim:

1. In a rail grinder, the combination with a movable carriage having on the operating side two wheels, one behind the other, adapted to move on one rail and on the other side 80 one or more supporting wheels of less diameter adapted to move on the other rail and so located as to cant the carriage downward on that side and a framework proximate the operating side with rigid vertical guideways, 85 of a rigid frame slidable in said guideways, a motor rigidly carried by the said frame, and bearings rigidly carried by said frame, an adjusting screw to raise and lower the frame in the guideways with reference to the 90 framework, a shaft in said bearings revoluble by said motor, and a grinding tool carried by said shaft in position to be brought in contact with the rail on the operating side by said adjusting screw, together with derailing wheels which project from the carriage on the operating side. 95

2. In a rail grinder, the combination with a movable carriage having on the operating side supporting means one behind the other 100 adapted to move on one rail, and on the other side supporting means adapted to move on the other rail and a framework proximate the operating side having rigid substantially 105 vertical guideways, of a rigid frame slidable in said guideways, a motor and bearings rigidly carried by said frame, a shaft in said bearings revoluble by said motor, a grinding tool revoluble with said shaft in position to engage the rail on the operating side, and 110 means to adjust the vertical relation between the frame and the framework, together with derailing wheels which project from the carriage on the operating side. 115

3. In a rail grinder, the combination with 115 a movable carriage having on the operating side supporting means one behind the other adapted to move on one rail, and on the other side supporting means adapted to move on the other rail and a framework 120 proximate the operating side having rigid substantially vertical guideways of a rigid frame slidable in said guideways, a motor and bearings rigidly carried by said frame, a shaft in said bearings revoluble by said 125 motor, a grinding tool revoluble with said shaft in position to engage the rail on the operating side, and means to adjust the vertical relation between the frame and the framework. 130

4. In a rail grinder, the combination with a movable carriage having on the operating side two wheels one behind the other adapted to move on one rail, and on the other side 5 supporting means adapted to move on the other rail, and a framework proximate the operating side having rigid substantially vertical guideways, of a rigid frame slidable in said guideways, a motor rigidly carried 10 by said frame, bearings rigidly carried by said frame, a shaft in said bearings revoluble by said motor, a grinding tool slidable on and revoluble with said shaft in position to engage the rail on the operating 15 side, and means to adjust the vertical relation between the frame and the framework, together with derailing wheels which project from the carriage on the operating side.

5. In a rail grinder, the combination with 20 a movable carriage having on the operating side two wheels, one behind the other, adapted to move on one rail and on the other side one or more supporting wheels of a different diameter adapted to move on the other 25 rail and so located as to cant the carriage, and a framework proximate the operating side with rigid substantially vertical guideways, of a rigid frame slidable in said guideways, a motor rigidly carried by the said 30 frame, and bearings rigidly carried by said frame, an adjusting screw to raise and lower the frame in the guideways with reference to the framework, a shaft in said bearings revoluble by said motor, a grinding tool 35 slidable on and revoluble with said shaft in position to engage the rail on the operating side, and derailing wheels which project from the carriage on the operating side.

6. In a rail grinder, the combination with 40 a movable carriage having on the operating side two wheels, one behind the other adapted to move on one rail, and on the other side one or more axles, a supporting wheel of a different diameter from the first named 45 wheels supported by each axle and slidable

thereon, a stop for each supporting wheel and a spring adapted to normally press each wheel against such stop, such supporting wheels being adapted to move on the other rail, derailing handles which project proximate the last named supporting wheels, and a framework proximate the operating side having rigid substantially vertical guideways, of a rigid frame slidable in said guideways, a motor rigidly carried by said frame, bearings rigidly carried by said frame, a shaft in said bearings revoluble by said motor, a grinding tool slidable on and revoluble with said shaft in position to engage the rail on the operating side, and means to adjust the vertical relation between the frame and the framework, together with derailing wheels which project from the carriage on the operating side, together with propelling handles attached to the carriage.

7. In a rail grinder, the combination with a movable carriage having on the operating side two wheels one behind the other adapted to move on one rail, and derailing wheels which project from the carriage, and on the other side one or more relatively light supporting wheels adapted to move on the other rail, together with derailing handles, of grinding mechanism including a grinding wheel, a motor, guideways, and mechanism for raising and lowering the motor and grinding wheel, such grinding wheel being located between the wheels on the operating side, the guideways, motor, grinding wheel and derailing wheels, being so positioned that when operating the center of gravity is proximate the operating side, and when derailing the derailing wheels will engage the ground about the time the center of gravity of the device is over the rail on the operating side.

In testimony whereof I have affixed my signature.

EPIPHANE P. SIMARD.
